ATTORNEY

UNITED STATES PATENT OFFICE

162,529

NECKTIE

Francis Alexander Innys Eveleigh-de Moleyns,
London England

Application April 29, 1950, Serial No. 9,577
In Ireland February 10, 1950

Term of patent 14 years

(Cl. D3—16)

To all whom it may concern:

Be it known that I, Francis Alexander Innys Eveleigh-de Moleyns, a British subject, residing at 65A Chester Square, London S. W. 1, England, have invented a new, original, and ornamental Design for a Necktie, of which the following is a specification, reference being had to the accompanying drawing, forming a part hereof.

Fig. 1 is a perspective view of a necktie showing my design.

Fig. 2 is an enlarged detail view in elevation of my design as shown in Fig. 1.

I claim:

The ornamental design for a necktie, as shown.

FRANCIS ALEXANDER INNYS
EVELEIGH-DE MOLEYNS.
